UNITED STATES PATENT OFFICE.

CHARLES H. NORTH, OF CLEVELAND, OHIO, ASSIGNOR TO THE NORTH ELECTRIC COMPANY, OF CLEVELAND, OHIO, A CORPORATION OF OHIO.

SPRING-JACK SWITCH.

No. 836,049.

Specification of Letters Patent.

Patented Nov. 13, 1906.

Application filed October 31, 1901. Serial No. 80,641.

To all whom it may concern:

Be it known that I, CHARLES H. NORTH, a citizen of the United States of America, and a resident of Cleveland, in the county of Cuyahoga and State of Ohio, have invented certain new and useful Improvements in Spring-Jack Switches, of which the following is a specification.

My invention relates to improvements in spring-jack switches for telephone-switchboards, and has for its object the provision of structural units of such switches constructed and mounted in the simplest and most durable manner, while at the same time avoiding disadvantages inherent in devices of the prior art.

It has been the common practice prior to my invention to mount spring-jack switches in convenient units of ten or twenty switches within the body of rubber strips suitably channeled and bored to surround and support substantially the entire spring-jack. Such construction necessarily is expensive, inasmuch as it involves the employment of special machinery and a high grade of workmanship for properly forming the rubber supporting-strip, which strip, in addition, is comparatively fragile, particularly when completely bored and grooved to accommodate the switch parts, and in consequence the damage or breakage of such strips in the course of manufacture is considerable. These strips of spring-jack switches, moreover, are upon some accounts quite as unsatisfactory to the user. The thin rubber walls of the honeycombed strip are very liable to break, particularly when subjected to low temperatures. The strips not infrequently warp out of shape, and accidental crossing of the connected wires with high-tension conductors sometimes impairs the insulation of the individual spring-jack switches, thus destroying the usefulness of the entire strip. When subjected to hard service, too, the weakened supporting-strip has been demonstrated not to be sufficiently rigid and substantial, the switch parts sometimes loosening therein and the lugs by which the strips are secured in place becoming worn and broken.

I have accordingly sought to overcome the observed defects and improve upon this class of switching apparatus in several important particulars specifically pointed out herein and in the appended claims.

The strip of spring-jack switches herein shown embodying my invention may be briefly described as consisting of a supporting or base plate, preferably of aluminium, along the front and rear edges of which are mounted relatively narrow strips of rubber, respectively carrying the test-thimbles and the switch-springs of the several jacks. The several switch-springs are peculiarly formed rearwardly with engaging shoulders to insure their being rigidly clamped in position and alinement in the rear insulating-strip. The inner or contact springs are stiffened to resist flexure, and the test-thimbles and their associated springs are made integral. Shaped mica insulating parts preferably are used between the springs, the shoulders provided thereon similar to those upon the springs preventing the displacement of said insulating parts.

For more detailed explanation of my improvements I will refer to the accompanying drawings, illustrating the said embodiment of my invention, wherein—

Figure 1 is a plan view of an improved strip of spring-jack switches, said strip being partially broken away and dismantled in a manner better illustrating its details of construction. Fig. 2 is a cross-sectional view on line 2 2, Fig. 1. Fig. 3 is an isometric view of a test-thimble and its integral connecting-spring. Fig. 4 shows a line-spring viewed from above and from the side; and Fig. 5 is a view of a single spring-jack switch, the three figures last named being made full size.

The same letter of reference is employed to designate similar parts in each of the several figures of the drawings.

Upon a plate *a*, preferably of heavy-gage sheet-aluminium, are mounted the front and rear strips *b c* of rubber or other suitable insulating material. The front strip is provided with a longitudinal shoulder *b'*, against which the plate abuts, and is laterally bored to receive the several test-thimbles *d* of the spring-jack switches.

I have chosen to show a strip of ten such switches, although double that number may as readily be mounted in the same space, if desired, since in my improved construction no insulating-walls are interposed between the bodies of the several spring-jacks. Hence the individual jacks may be made of somewhat larger size and still be mounted on

standard centers, just enabling the outer line-spring *e* when flexed by the inserted plug to clear the adjacent switch part.

The front strip *b* is secured to the plate *a* 5 by screws *b''*. Ten grooves *c'* are formed in the rear strip *c*, wherein the assembled switch parts of the several jacks are adapted to be inserted and rearwardly supported, the same forming a rearwardly grooved or channeled 10 mounting-strip for spring-jacks.

Each individual jack comprises two line-springs *e f*, two contact-springs or anvils *e' f'*, coacting therewith, a test-thimble *d* and its integral connecting spring or part *d'*, and 15 interposed mica insulators *g g'*. All of these preferably are shaped to afford front and rear abutting shoulders *h*, (best shown in Figs. 2 and 4,) which engage either side of the insulating-strip *c*, and a superposed mica 20 strip *i*, extending the length of the said strip of jacks.

The test-thimbles *d*, which are stamped out of and suitably shaped, together with their connecting-springs *d'*, from a single 25 piece of sheet metal, are inserted in the openings provided in the front strip *b* and secured therein by means of flush-pins *d''*. Said thimbles are slightly countersunk and reamed out to present a uniform bore for the connecting-plug. 30

A narrow metal strip *k*, placed above the mica strip *i*, seats the screws *k'*, which are inserted upon either side of each spring-jack switch, said screws serving to secure the several strips to the plate and binding down the strips *i k* to clamp the jacks rigidly in their respective grooves. 35

The several switch parts preferably are stamped from German silver, the engaging 40 springs being provided with platinum contacts, as *e'' f''*. The line-springs are given an inward set, as seen in Fig. 4, to insure their normal contact with the coacting contact-springs. Said contact-springs *e' f'* are 45 formed of relatively heavy-gage metal and are provided with interposed stiffening-insulators *g'* to minimize or prevent their flexure by the unequal action of the line-springs during the insertion and removal of the connecting-plug *l*. This serves at such times to 50 maintain the alinement of the said line-springs with the thimble and facilitates the entrance and withdrawal of the plug. The projecting ends *a'* of the plate *a* serve to support the strip of jacks in position upon the 55 switchboard, which may be built up of numerous superposed strips in the well-known manner. The connecting-wires of the associated conductors in the telephone-exchange 60 are electrically united with the several switch parts by soldering said wires, respectively, to the perforated diverging extremities of said switch parts.

Mere explanation of the illustrated structure will insure full appreciation of the fact

that many disadvantages found in the devices of the art have been eliminated and overcome by my improvements. The strip of spring-jacks is durable and quite cheaply constructed. It will not warp out of alinement and is adapted to withstand the severest service. 70

The narrow rubber insulating-strips are easily constructed, effecting a saving both in labor and material over the devices of the prior art. Should said insulating-strips accidentally become cracked or broken, the utility of the completed strip of spring-jacks will not be impaired, since the metal base-plate *a* will securely retain the broken portions in position. The longitudinal thrust exerted by the plug upon the springs is taken up by the abutting shoulders *h* and the rear insulating-strip in which said springs are anchored. 80

The several parts are freely accessible for inspection and repair, and accumulated dust and dirt may be easily removed from the strip. The mica insulation by which the individual springs are electrically separated is practically imperishable and is not impaired by high-tension currents, which sometimes injure jacks mounted between thin rubber insulating parts. 85

Having now described my improved spring-jack and the novel manner of mounting the same in strips for use, I claim, together with such modifications thereof as are by law implied, the following: 90

1. In a spring-jack switch, the combination with the line-springs *e f*, of their coacting contact-springs or anvils *e' f'*, an integral test-thimble and bowed connecting-spring *d d'* shaped from a single piece of sheet metal, said springs being provided with similar mounting-terminals and closely assembled in substantially parallel planes, and a rearwardly-channeled mounting-strip wherein all of the parts are mounted, substantially as set forth. 100

2. In a strip of spring-jack switches, the combination with a relatively narrow strip of insulating material, the same being channeled or grooved, of separate spring-jack parts mounted within the grooves, comprising line-springs and a test-thimble and its connecting-spring, and thin insulating parts disposed therebetween; the said springs and insulating parts being rearwardly formed with abutting shoulders *h* adapted to embrace the narrow, insulating, mounting-strip and secure the several parts of the jacks within their respective grooves, and a superposed insulating-strip coöperating in retaining the parts in position, substantially as set forth. 110

3. In a spring-jack switch, the combination with the inner contact-springs or anvils, of the long and short line-springs pressing against said contact-springs from opposite 120 125 130

sides, and a sleeve through which the connecting-plug is inserted to contact with the two line-springs in succession, the said inner contact-springs or anvils being suitably stiffened, and thus adapted to preserve the alinement of the line-springs during the insertion and withdrawal of the plug, substantially as set forth.

4. In a strip of spring-jack switches, the combination with a metal base-plate *a*, of a front strip *b* having an abutting shoulder *b'* secured along the forward edge of said plate, a channeled strip *c* mounted upon its rear edge and a plurality of spring-jack switches mounted upon said strips *b c*, said plate and rear strip being firmly secured together upon either side of each of the mounted spring-jacks, substantially as set forth.

5. In a strip of spring-jack switches, the combination with a flat base-plate *a*, of narrow front and rear insulating-strips *b c* mounted along the edges thereof, said strips being respectively bored to receive the test-thimbles and grooved to accommodate the rear or mounting portions of the spring-jack switches, and a plurality of spring-jack switches mounted in the grooves with all the parts thereof upon edge, said switches extending between the said insulating-strips and supported thereby above the level of the base-plate, their body portions being uninclosed and thus made freely accessible, substantially as set forth.

6. In a strip of spring-jack switches, the combination with an aluminium plate *a*, of insulating-strips *b c* secured along its front and rear edges, the former being bored to receive the test-thimbles and the latter grooved to accommodate and support the rear portions of the several switch parts, a plurality of spring-jack switches carried by said insulating-strips and a superposed and insulated strip *k* clamping the jacks within the strip *c*,

said strips and plate being rigidly secured together, substantially as set forth.

7. In a spring-jack switch, the combination with the line-springs *e f*, of the test-thimble and its bowed connecting-spring, spacing-insulators disposed therebetween; all of said parts being provided with similar mounting-terminals and closely assembled in substantially parallel planes, and a rearwardly-channeled supporting-strip wherein all of the parts are mounted, substantially as set forth.

8. In a strip of spring-jack switches, the combination with a metal base-plate *a*, of a front strip *b* secured along the forward edge of said plate, a channeled strip *c* mounted upon its rear edge, and a plurality of spring-jack parts mounted upon the rear strip, said plate and strip being firmly secured together upon either side of each of the mounted spring-jacks, substantially as set forth.

9. In a strip of spring-jack switches, the combination with a mounting-strip of insulating material, the same being grooved or channeled substantially its entire depth to provide mountings for the spring-jack switches, of a plurality of spring-jack switches respectively mounted in said grooves, and a superposed and insulated strip of metal firmly securing the spring-jack switches within their respective grooves in the mounting-strip; said superposed strip being united with the mounting-strip between the grooves and serving also to stay or strengthen the weakened mounting-strip, substantially as set forth.

Signed by me, in the presence of two subscribing witnesses, at Cleveland, Ohio, this 29th day of October, A. D. 1901.

CHARLES H. NORTH.
